(57) **CLAIM**

The ornamental design for an absorbent product dispenser, as shown and described.

DESCRIPTION

FIG. 1 is a perspective view showing our new design for an absorbent product dispenser;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines immediately adjacent to the shaded areas in the figures represent the boundaries of the claimed design. The broken lines in the figures illustrate the portions of the absorbent product dispenser that form no part of the claimed design. None of the broken lines form any part of the claimed design.
